UNITED STATES PATENT OFFICE.

LUCIAN W. BUGBEE, OF INDIANAPOLIS, INDIANA, ASSIGNOR, BY MESNE ASSIGNMENTS, TO CONTINENTAL OPTICAL CORPORATION, OF NEW YORK, N. Y., A CORPORATION OF DELAWARE.

MACHINE FOR GENERATING TORIC SURFACES ON LENSES.

Application filed July 23, 1923. Serial No. 653,367.

The object of this invention is to improve the construction and operation of apparatus for generating toric lenses, whereby several advantages are obtained and 5 wherein there is a grinder having a grinding periphery for grinding and determining the curvature of the lens in one principal meridian and a lens holder pivotally mounted and oscillatable tangentially of the grinder with a radius of oscillation such as to 10 predetermine the curvature of the lens in the other principal meridian.

In the apparatus shown herein the transverse curvature of the periphery of the 15 grinder determines the meridional curvature and the radius of oscillation of the lens holder as the grinder determines the equatorial curvature.

One feature of the invention consists in 20 having a radially adjustable lens holding bar whereby the equatorial curvature of the lenses is determined merely by the radial adjustment of the lens holding bar. When a spotting wheel or the like is used in an apparatus of this kind to vary the equatorial curvature of the lens, it requires the replacing of the spotting wheel by another spotting wheel, and, therefore, a considerable stock of spotting wheels must be carried. That expense and annoyance is made 25 unnecessary by this simple improvement, where a small lens holding bar is adapted, by radial adjustment, to determine any distances of equatorial curvatures that may be 30 desired. In such apparatus the meridional curvature is determined by the transverse peripheral form of the grinding wheel, the same as in prior apparatus for grinding 35 toric lenses.

40 The lens holding means is oscillatable in the plane of the grinder and is non-rotary and has no other movement than said oscillatable movement. This movement is preferably effected by hand.

45 This apparatus is particularly well adapted where toric lenses are to be ground for single prescriptions, and it is also very advantageous to small and retail opticians and optical concerns where the lenses are ground 50 as single prescriptions. Heretofore the optician or optical concerns have been required to have in stock quite a large number of tools, one for each possible combination that may be required in the business. Hence,

this greatly cheapens the equipment for optical retailers.

The full nature of the invention will be understood from the accompanying drawings and the following description and 60 claims.

In the drawings, Fig. 1 is a side elevation of said machine illustrating this invention, parts of the grinder being broken away and the lens block being shown in different positions assumed while the lens is being ground. 65 Fig. 2 is a plan view of the machine.

In the machine herein shown for the purpose of illustrating the general nature of this invention, there is a table or base plate 10 on which is mounted a plate 11 carrying two bearing posts 12 for an arbor shaft 13, on one end of which a grinding wheel 14 is removably secured and which is driven by a pulley 15 secured on the arbor 13 between the two bearings 12. 70

75 There is also shown herein a truing device which constitutes no necessary part of this invention, but which consists of an adjustable plate 20 mounted on the main plate or table 10 and with a key 21 on the under side 80 projecting in the keyway 22, and which plate is angularly adjusted by bolts 23 extending up from the main plate 10 through slots 24 in the plate 20. The plate 20 carries a post 25 in which is mounted a pointer or 85 centering pin 26.

90 There is also a plate 30 mounted on the main plate 10 and having on its under side a key 31 projecting into a keyway 32 in the main plate or table 10. A post 33 extends upward from the plate 30, and at the upper end of it there is a horizontal fulcrum pin 34 carrying a nut 35 and having a shoulder 36 set in a recess 37 in the post 33 between which a lens holding block or 95 bar 40 may be secured on said fulcrum 34 and clamped against the shoulder 36 by the nut 35. There is a nut 38 for holding said fulcrum pin 34 in said post 33 but so the pin can turn. The lens holding bar 40 is 100 thus held in the same plane as the grinder 14, and so that a lens blank 42 secured on the end of said holder 40 may engage the periphery of the grinder, as shown.

105 The lens holding bar has a longitudinal slot through which the fulcrum 34 extends, whereby the lens holder is adaptable to use with grinding wheels of varying diameters,

but the main advantage is the radial adjustability of the lens holding bar for varying the radius of the equatorial curvature of the lenses. All that is necessary for changing the apparatus to vary the equatorial curvature of the lenses is to loosen the nut 35, slide the lens holder longitudinally to a position which gives the radius for the desired equatorial curvature, and then tighten 10 the nut.

On the lens holding bar 40 a scale of numerals 43 is marked representing diopters, and by adjusting the position of the bar to bring any part of said scale into registry 15 with the mark 44 on the post 33 or some other stationary indicator, one is enabled quickly to adjust the lens holding bar to obtain any desired equatorial curvature. The lens blanks are secured by pitch or the 20 like on lens block 45 which has a hub-like extension projecting into a round aperture in the end of the lens holder where it is secured by a set screw 46.

The meridional curvature is determined 25 by the transverse surface of the periphery of the grinding wheel in this machine as in other toric generating machines. In operating the apparatus, the plate 30 carrying the lens holding bar must be set so as to 30 bring the lens blank in contact with the periphery of the grinding wheel. This adjustment of the plate will be necessary whenever the lens holding bar is adjusted, and it is also necessary when there is a change 35 of grinding wheel or when it is necessary to change the position of the plate 30 to accommodate the apparatus with the wear or reduction in diameter of the grinding wheel. The plate 30 is held in adjusted position by 40 bolts 39 which extend from the base plate 10 to the slots 130. The construction is also such that the midline longitudinally of the lens holding bar 40 will be in line with the midline of the grinding wheel and of the 45 truing point 26.

The lens holder is mounted so that it is not rotatable and the lens holding means has no movement except the oscillation thereof in the plane of the grinder and this 50 oscillation is preferably manual so that the lens can be properly fed to the wheel by the manual operation and observation of the operator.

In operation, a lens is placed on the end of 55 the lens holder 40, and said lens holder is set at the desired diopter and the grinding wheel rotated, and the lens holder 40 brought to either one of the dotted line positions shown in Fig. 1, where the grinder will begin to grind the lens and then the operator 60 continually but slowly oscillates the lens holder from one of the dotted line positions to the other. This is done by the handle 41. One movement of the lens holder will roughly 65 grind the lens. Then the operator oscillates

the lens holder back and forth throughout its entire arc several times, thus rapidly bringing the lens in touch with the grinder in order to grind out any lines in the lens and perfect and finish the grinding thereof. 70

It is preferable to make the diopter scale 43 slidable and adjustable longitudinally of the lens bar 40, as shown in Fig. 1. This is desirable because the lens blocks 45 are of different thicknesses and so are the lens 75 blanks 42, and their variation in thickness is compensated for by corresponding adjustment of the sliding scale bar 43. As seen in Fig. 1 the scale bar has a key operating in a dovetail groove in the lens bar 80 40. In this way the apparatus can be set with absolute accuracy.

Also for varying the axes of the toric lens according to any need or prescription, a scale 50 is provided on the end of the lens bar 40, as seen in Fig. 2, with which a mark 51 on the lens block 45 is adapted to register. By slightly turning the lens block 45 one way or the other, the desired angular 90 adjustment of the lens is attained, whereby the lens when ground will have the axes called for by the prescription. 95

The details of the construction herein shown to illustrate the invention may be varied without departing from the spirit of the invention, as expressed in the claims. 100

The invention claimed is:

1. In a machine for generating toric surfaces on lenses, a fixed rotary grinder with its periphery curved transversely so as to determine the curvature of the lens in one principal meridian, a lens holder oscillatable in the plane of the grinder for moving the lens to and past the grinding radius of the grinder, a relatively fixed fulcrum for said lens holder, and means permitting varying the radius of oscillation of the lens holder to predetermine the arc of travel past the grinder and thereby the curvature of the lens in the other principal meridian. 110

2. In a machine for generating toric surfaces on lenses, a fixed rotary grinder with its periphery curved transversely so as to determine the curvature of the lens in one principal meridian, a lens holder oscillatable in the same plane as the grinder for moving the lens to and past the grinding radius of the grinder, and a relatively fixed fulcrum for said lens holder on which the lens holder is radially adjustable permitting varying the radius of oscillation of the lens to predetermine the arc of travel past the grinder and thereby the curvature of the lens in the other principal meridian. 115

3. In a machine for generating toric surfaces on lenses, a rotary grinder with its periphery shaped in cross section so as to determine the meridional curvature of the lens, a longitudinally slotted bar for holding the lens on the end thereof against the 125 130

- grinder, a fulcrum pin extending through said slot, stationary means in which said fulcrum pin is mounted so that it will oscillate, means for clamping the lens holding bar on said fulcrum pin when adjusted, and a handle for oscillating the lens holding bar in the same plane as the grinder.
4. A machine for generating toric surfaces on lenses including a base plate, a grinding wheel, means mounted on said plate for supporting the grinding wheel, means for rotating the grinding wheel, the periphery of said grinding wheel being shaped in cross section so as to form the meridional curvature of the lens, a post mounted on said base plate and adjustable toward and away from said grinder, means for fastening it in adjusted position, a rotatable fulcrum pin mounted in said post parallel with the axis of the grinding wheel, a lens holding bar with a longitudinal slot in it through which said fulcrum pin extends, and means for clamping said bar on said pin when adjusted, whereby said bar may be oscillated to move a lens carried thereby tangentially into contact with and past the grinding radius of the grinding wheel.
5. A machine for generating toric surfaces on lenses including a base plate, a grinding wheel, means mounted on said plate for supporting the grinding wheel, means for rotating the grinding wheel, the periphery of said grinding wheel being shaped in cross section so as to form the meridional curvature of the lens, a post mounted on said base plate and adjustable toward and away from said grinder, means for fastening it in adjusted position, a rotatable fulcrum pin mounted in said post parallel with the axis of the grinding wheel, a lens holding bar with a longitudinal slot in it through which said fulcrum pin extends, and means for clamping said bar on said pin when adjusted, whereby said bar may be oscillated to move a lens carried thereby tangentially into and contact with and past the grinding radius of the grinding wheel, said lens holding bar having a diopter scale thereon and said post having an indicating mark with which said diopter scale is adapted to register, whereby the lens holding bar can be readily set to obtain the desired equatorial curvature of the lens.
6. In a machine for generating toric surfaces on lenses, a rotary grinder with its periphery curved transversely so as to determine the curvature of the lens in one principal meridian, a lens holding bar oscillable for moving the lens to and past the grinding radius of the grinder, a relatively fixed fulcrum for said lens holding bar, means permitting varying the radius of oscillation of the lens holder to predetermine the arc of travel past the grinder and thereby the curvature of the lens in the other principal meridian, and a lens holding block in the end of said bar which is angularly adjustable for varying the axis of the lens.
7. In a machine for generating toric surfaces on lenses, a rotary grinder with its periphery curved transversely so as to determine the curvature of the lens in one principal meridian, a lens holding bar longitudinally slotted, a relatively fixed fulcrum extending through said slot in the lens holding bar so that the lens holding bar may be oscillatable for moving the lens to and past the grinding radius of the grinder and be radially adjustable for determining the arc of travel past the grinder and thereby the curvature of the lens in the other principal meridian, and a lens holding block in the end of said bar which is angularly adjustable for varying the axis of the lens.
8. In a machine for generating toric surfaces on lenses, a rotary grinder with its periphery curved transversely to determine the curvature of the lens in one principal meridian, a lens holding means, a fulcrum for said lens holding means located on the same side of the grinder as the lens holding means and which enables the lens holding means to be oscillated for moving the lens to and past the grinding radius of the grinder, and means permitting varying the radius of oscillation of the lens holder to predetermine the arc of travel past the grinder and thereby the curvature of the lens in the other principal meridian.
9. In a machine for generating toric surfaces on lenses, a rotary grinder with its periphery curved so as to be concave transversely to generate the desired curvature of the lens in one principal meridian, a lens holding means, a fulcrum for said lens holding means which enables the latter to be oscillated in the plane of the grinder for moving the lens to and past the grinding radius of the grinder for line grinding the lens, and means permitting varying the radius of such oscillation of the lens holding means to determine the arc of travel past the grinder and thereby the curvature of the lens in the other principal meridian.
- In witness whereof, I have hereunto affixed my signature.
